LIMIT CONTROL SYSTEM FOR REVERSIBLE MOTORS

Asa H. Myles, Solon, Ohio, assignor to The Electric Controller & Manufacturing Company, Cleveland, Ohio, a corporation of Ohio

Application July 13, 1949, Serial No. 104,575

9 Claims. (Cl. 318—263)

1

This invention relates to controllers for electric motor driven machinery, and more particularly to a motor control system including improved limit control circuits of the variable impedance type.

While not limited thereto, the present invention is especially advantageous for controlling the motor which drives a reciprocating machine element between preselected limits. In order to increase the rate of production of many large machines of this type, the speed of the reciprocating element has been increased to such an extent that it is no longer feasible to use track type limit switches or other limit switches requiring physical contact between the moving element and a switch operating lever. Furthermore, in many machines having reciprocating elements, such as reeler bars, for example, the path of travel of the reciprocating element is not sufficiently definite to permit the use of prior variable impedance limit control circuits not requiring such physical contact. Consequently, the problem of controlling such machines has not heretofore been adequately solved, particularly in the provision of limit control means capable of providing the desired accuracy and safety with reasonable endurance under extremely severe operating conditions.

Prior known variable impedance type limit control circuits operating at low frequency and without electronic devices have comprised only a series connected reactor and relay. A magnetic operating member or vane when moved into the field of the reactor increases the impedance of the reactor so that the relay current, which varies in inverse proportion to the circuit impedance, decreases to a value permitting drop-out of the relay. It is because of the small reduction in relay current that is obtained, particularly when considerable clearance must be provided between the vane and the reactor, that such prior limit control circuits cannot be used for large industrial machines of the type herein contemplated in which the path of travel of the moving magnetic member is erratic so that the vane is apt to strike the reactor or pass at so great a distance therefrom that insufficient current change results. Additionally, since at constant voltage only a small reduction in relay current occurs in these prior limit control circuits, normal increases in the supply voltage often cause a false operation by maintaining the relay energized even though the magnetic vane is in the reactor field.

It is an object of the present invention to provide a motor control system solving the aforementioned problems.

2

Another object is to provide a motor control system including an improved limit control circuit of the variable impedance type.

One of the important features of the present invention is the provision of a reactor of relatively low inductance having its poles arranged to define an elongated concentrated leakage field the reluctance of which can be materially decreased by movement of a magnetic vane therein

5 10 15 20 25

at a considerable distance from the pole faces, combining the reactor in a low frequency tuned circuit with a capacitor and a relay which has a very small differential between its pick-up and drop-out current values, and supplying the tuned circuit with a low frequency voltage of such low value that the relay current at resonance is limited without adding resistance to the circuit other than that inherent in the reactor and relay winding or that used to decrease the relay differential.

Accordingly, a further object is to provide a limit control circuit operative at low frequency in which a relay is operated directly by current change resulting from a disturbance of the ratio between capacitive and inductive reactance in the circuit.

Another object is to provide a tuned limit control circuit including a reactor, a capacitor, and a relay which is held closed by the current in the circuit preferably at or near the peak of resonance and which drops out upon that impairment of the resonant conditions resulting from movement of a metallic vane into the leakage field of the reactor.

Another object is to provide an improved variable impedance limit control circuit including a resonant circuit but not utilizing electronic devices.

Still another object is to provide a low frequency limit control circuit including a reactor and operative when either a magnetic or a non-magnetic metallic vane is moved into the reactor field.

The limit control circuit in accordance with this invention includes a reactor having widely spaced poles defining a single elongated leakage field and connected in series with a series-connected capacitor and relay winding across a source of relatively low voltage and frequency. The circuit is tuned for resonance when the leakage field contains substantially no metal. The relay has a small differential between its pick-up and drop-out current values and is held closed by the circuit current at resonance. The small differential may be an inherent feature of the relay or may be obtained by causing the relay to connect a resistor in shunt with its winding

when the relay picks up. A moving element of the machine to be controlled carries a metal vane which moves into the leakage field thereby impairing the resonance of the circuit and causing the relay to drop out. Preferably the vane is of magnetic metal, but a non-magnetic metal vane also can be used to obtain an accurate response. The control system is arranged to utilize relays responding as just described to slow down the motor as the machine approaches opposite limits of its travel and to stop the machine at the limits. A novel interlocking arrangement is provided which permits both slow-down and stop control functions to be performed at both limits of travel by using four reactors but only two relays in the resonant circuits.

A more specific object of the invention is to provide a limit control circuit comprising a reactor, a capacitor, and an electromagnetic relay having an operating winding all connected in a series circuit arranged for connection across a source of alternating current of constant and low frequency, the electrical constants of the series circuit being so related to each other and to the voltage and frequency of the source that the relay picks up when the circuit is connected to the source with the leakage field of the reactor substantially free of conducting material, and the electrical constants of the series circuit being further so related to each other and to the voltage and frequency of the source that the series circuit is substantially resonant when the relay is picked up, the current that flows in the circuit at resonance being sufficient to hold the relay in its picked up position, together with extraneous means for so varying the reactance of the reactor that the resonance of the circuit can be impaired sufficiently to permit drop-out of the relay.

Other objects and advantages will become apparent from the following description wherein reference is made to the drawings, in which

Fig. 1 shows the limit control circuit diagrammatically, the reactor with its cover removed and the machine to be controlled being shown schematically.

Fig. 2 is a schematic side elevation of the reactor and a portion of the controlled machine,

Figs. 3 and 4 are graphs illustrating features of the invention, and

Fig. 5 is a wiring diagram of a complete control system utilizing a plurality of the limit control circuits of Fig. 1.

Referring to Fig. 1 a limit control circuit in accordance with this invention comprises a reactor 10, a capacitor 11 which may be adjustable, and an operating winding 12w of an electromagnetic relay 12 all connected in a series circuit with each other across a tapped low voltage secondary winding 14s of a step-down transformer 14 having its primary winding 14p supplied from a source 15 of alternating current at the usual low frequency of electric power supply systems. The constants of the circuit are so selected with respect to each other and the voltage and frequency of the source that when the relay 12 is closed the circuit is resonant and the resonant current holds the relay closed. Means to be described are provided for changing the reactance of the reactor 10 thereby to impair the resonant condition effecting a reduction in the current in the winding 12w to a value materially below the drop-out current value of the relay 12.

The effect of the condenser 11 on the current in the relay winding 12w upon an increase in the

reactance of the reactor 10 is graphically shown in Fig. 3 wherein relay current is plotted against the inductive reactance of the circuit. A curve 16 in Fig. 3 shows the operating characteristic of a circuit such as that of Fig. 1, whereas a curve 17 shows the operating characteristics of a similar circuit but without a capacitor. Since the combined inductive reactance of a series connected reactor and relay winding must have some finite value, a variable impedance limit control circuit without a capacitor must be operated along the flat portion of the curve 17 at a material distance from the vertical axis. By adding a capacitor to the circuit, the operating characteristic is moved to the right as shown by the curve 16, and the circuit can be operated along the steep part of the curve 16 from a maximum current value at X limited only by the resistance of the circuit to a lower value at the point Y where the curve 16 begins to flatten out. Although it is preferred that, when the relay is picked-up and the reactor is at its normal reactance value, the limit control circuit is exactly in resonance, an approximate resonant condition providing the desired degree of current change upon impairment of the approximate resonant condition is also satisfactory. It is seen, by comparing the curves 16 and 17, that a limit control circuit including a capacitor if made approximately resonant can be made to have a very much larger current variation in the working range for a given change in inductive reactance than can a circuit without such capacitor.

Referring now to Figs. 1 and 2, the reactor 10 comprises a case 18 preferably formed of insulating material or non-magnetic metal and containing a U-shaped laminated magnetic core 19 having multi-turn windings 20 upon its respective legs. The windings 20 are connected in series with each other and in such manner that the respective fluxes produced thereby are additive. The core 19 preferably has sufficient cross-section to minimize the effect of magnetic saturation. The legs of the core 19 are spaced apart a material distance and extend toward and substantially engage a relatively thin, gasketed, non-metallic cover 21 for the case 18, the cover 21 preferably being formed from Bakelite or other suitable insulating material. When the coils 20 are energized, an elongated leakage field extending lengthwise of the case 18 is produced which is concentrated in the region adjacent to and outside of the cover 21. In order to minimize the voltage across the capacitor 11 at resonance, it is desirable to make the inductance of the reactor 10 relatively low as by using relatively few turns in the windings 20.

The relay 12 has a pair of normally-open contacts 12a and 12b and preferably has a very small differential between its pick-up and drop-out current values. In order to provide the desired small differential and to render the amount of differential adjustable, the contacts 12a may be arranged to connect a variable resistor 22 in parallel with the winding 12w when the relay 12 is in its energized position. Preferably, the secondary winding 14s of the transformer 14 is provided with taps 14a so that the voltage applied to the limit control circuit can be adjusted readily to compensate for variations in the voltage of the source 15 or for manufacturing tolerances in the reactor 10, relay 12, and capacitor 11. The contacts 12b of the relay may be used to control an external circuit in a manner to be described in connection with Fig. 5.

The constants of the limit control circuit are so selected with respect to each other and to the voltage and frequency of the source 15 that the limit control circuit is substantially resonant when a magnetic vane 24 is not in the leakage field of the reactor 10. When the limit control circuit is resonant, the current in the circuit is above the pick-up current value of the relay 12 and the relay 12 is in its energized position, the resistor 22 is connected in parallel with the winding 12w through the contacts 12a, and the contacts 12b are closed. Before the relay 12 picks up, the inductive reactance of the circuit is slightly less than the capacitive reactance, the two reactances preferably becoming substantially equal when the relay 12 closes. When the vane 24 is in the leakage field of the reactor, the reactance of the reactor is increased and the resonance of the limit control circuit is impaired. The impairment of resonance causes the current in the relay winding 12w to be very much less than its value under resonant conditions and the relay 12 is dropped out. When the relay 12 drops out, the reactance of its winding 12w is decreased. In so far as current flow in the limit control circuit is concerned, the decrease in the reactance of the winding 12w upon drop-out of the relay 12 is compensated for by the much greater increase in the reactance of the reactor 10 and also to a lesser extent by the increase in resistance of the circuit resulting from the disconnection of the resistor 22 upon opening of the contacts 12a. Due to eddy currents induced in the magnetic vane, the effective resistance of the circuit is also increased when resonance is impaired. The increase in effective resistance also effects a reduction in the non-resonant current.

If the vane 24 is made of non-magnetic conducting material, the relay 12 also responds to movement of the vane into the reactor field. This is because the conducting material effects a decrease in the impedance of the reactor 10 which also impairs the resonance of the limit control circuit resulting in a reduced current flow therein as indicated by the portion Z of the curve 16 in Fig. 3. If the circuit did not include a capacitor, a non-magnetic conducting vane would cause an increased current to flow to the relay.

Although the limit control circuit may be applied in various ways and for numerous applications, its operation is described herein in connection with a machine having a base member 25 upon which the reactor 10 is mounted as by suitable bolts. The base member 25 carries a moving machine element 26 slidable lengthwise of the base 25 in ways 28. The magnetic vane 24 is suitably supported on the machine element 26 so that as the element 26 moves back and forth along the base 25 the vane 24 moves in a path parallel to and spaced from the cover 21 and into and out of the leakage field of the reactor 10. The vane 24 is preferably the same size as the cover 21 or slightly larger. Well known means (not shown) may be employed to provide for adjustment of the position of the reactor 10 lengthwise of the base 25 or of the position of the vane 24 on the element 26 or both.

The contacts 12b may be arranged to permit, when closed, operation of a motor (not shown) driving the element 26 and to prevent operation of the motor when open. Thus, should there be a failure of power in the limit control circuit, the relay 12 opens the contacts 12b to prevent operation of the motor. When the vane 24 is moved into the leakage field of the reactor 10 due to movement of the element 26, the relay 12 drops

out as described above to effect stopping of the motor and the element 26. The decrease in the current in the relay winding 12w as the vane 24 moves into the leakage field of the reactor is graphically illustrated by the curve 29 of Fig. 4, wherein the value of relay current is plotted against the distance between the approaching edge of the vane 24 and the longitudinal center line of the reactor 10. Because of the relatively great decrease in relay current for a small change in the reactance of the reactor 10 resulting from the impairment of resonance, and because of the small differential between the pick-up and the drop-out current values of the relay 12, the vane 24 may be so mounted that its path of movement is at a considerable distance from the reactor 10 and still obtain accurate operation of the relay 12. Hence, it is possible to use the limit control circuit where alignment between the base 25 and the element 26 is very erratic. Although in some instances the poles of the variable reactor could be arranged to define a slot through which the vane is moved, or could be aligned with each other as in a bar magnet to operate in conjunction with a U-shaped vane, such arrangements become impractical where the path of the vane is not accurately predetermined. By providing a reactor having a U-shaped core defining an elongated leakage field so that its reactance can be changed even though large clearance is provided between the reactor and the vane, combining the reactor with a capacitor to provide a tuned circuit, and utilizing a close differential relay, the applicant has obtained an improved variable impedance limit control circuit of increased utility.

When the voltage supplied to the limit control circuit of Fig. 1 is as high as that commonly used in industrial plants for lighting service, for example 110 or 220 volts, and the relay is of rugged construction, it has been found that the voltage drop across the capacitor at resonance becomes too great for economical capacitors of low voltage rating. By using the step-down transformer 14, the voltage across the capacitor can be kept at a reasonably low value by making the reactance of the reactor at resonance relatively low. The resistance of the circuit is less when the reactance is small because of the few turns required in the windings 20, hence the low voltage serves to limit the relay current to a safe value at resonance. The low resistance of the circuit causes the portion of the curve 16 of Fig. 3 between the points X and Y to be much steeper than it would be if the circuit had a higher resistance.

Referring now to Fig. 5, a plurality of limit control circuits similar to the circuit of Fig. 1 and having a plurality of respective reactors 30, 31, 32 and 33 each of which is similar to the reactor 10 are shown for controlling a motor 34 arranged to drive a cable drum 35 thru suitable shafting 36 and gearing 37. The motor 34 which may be of any suitable type is shown as a direct current series machine having an armature winding 34a and a series field winding 34b. A cable 38 wound upon the drum 35 and an idler drum 39 is connected to a carriage 40 of a reel bar having a base member 41. Operation of the motor 34 drives the drum 35 causing the cable 38 to move the carriage 40 back and forth along ways 42 formed on the base member 41. The carriage 40 may carry a piercing mandrel 43 and a magnetic vane 44 similar to the vane 24. When the carriage 40 is moved to the left or forwardly into a locking head 45, it may be locked thereby against movement along the base. When in locked position, a billet of hot metal is forced

over the mandrel 43 by suitable means (not shown). After a sufficient length of the billet has been pierced by the mandrel 43, the motor 34 is operated to reverse the carriage 40 and return it to the right to withdraw the mandrel and to await another piercing operation. In order to increase the production of the reeler bar it is necessary that the carriage 40 travel with great rapidity between its two extreme limiting positions. Heretofore, track type limit switches have been used to effect slow down and stopping of reeler bar carriages. It has been found, however, that track type limit switches are not rugged enough to withstand repeatedly for long periods the severe duty imposed upon them by the high speed desired of modern reeler bar carriages. Because the limit control circuit of the present application operates with no physical contact between the moving and the stationary elements and with wide variations in alignment therebetween, many advantages result from its use.

The reactors 32 and 33 are arranged to be connected to complete forward and reverse slow down limit control circuits, selectively, and are adjustably mounted near opposite ends of the base 41 in the proper position to effect slow down of the motor 34 as it drives the carriage 40 with its vane 44 toward its opposite extreme limits. The reactors 30 and 31 are arranged to be connected to complete forward and reverse final limit control circuits, selectively, and are adjustably mounted substantially at the extreme limits of travel of the carriage 40 adjacent the path of travel of the vane 44 to effect final stopping of the motor 34 after it has been slowed down.

The various limit control circuits of Fig. 5 are supplied from a transformer 46 similar to the transformer 14 and arranged to be connected to a source of low frequency alternating current 47 by a knife switch 48. Depending upon the direction of motor rotation, the reactors 32 and 33 are arranged to be connected in series selectively with a series connection comprising an adjustable capacitor 49 and an operating winding 58w of an electromagnetic slow-down relay 50, and the reactors 30 and 31 are arranged to be connected in series selectively with a series connection comprising an adjustable capacitor 51 and an operating winding 52w of an electromagnetic final limit relay 52. The relay 50 has normally-open contacts 50a and 50b and the relay 52 has normally-open contacts 52a and 52b. The relays 50 and 52 preferably have a close differential between their respective pick-up and drop-out current values which close differential may be provided in any suitable manner or as shown in Fig. 1.

The motor 34 is arranged to be connected in series with the operating winding of a spring-applied, electromagnetically released friction brake 54, an acceleration resistor 55 having a plugging section 55p, and an operating winding 56w of a suitable overload relay 56 having normally closed contacts 56a.

A forward electromagnetic contactor 60 has normally open contacts 60a and 60b arranged to connect the motor 34 to a suitable direct current source 61 for forward operation and a reverse electromagnetic contactor 62 has normally open contacts 62a and 62b arranged to connect the motor 34 to the source 61 for reverse operation. A main line electromagnetic contactor 63 has a normally open contact 63a arranged to complete the motor connection to one side of the source 61

61 for both directions of rotation. Slow down of the motor 34 prior to stopping is effected by an armature shunt contactor 64 having normally-closed contacts 64a arranged to connect a resistor 55 in parallel with the armature winding 34a. A plugging contactor 66 has normally open contacts 66a arranged to short circuit the plugging section 55p of the resistor 55, and an acceleration contactor 68 has normally open contacts 68a arranged to short circuit the remainder of the acceleration resistor 55. Operation of the contactor 66 may be controlled automatically by a suitable normally-closed plugging relay 69 and the operation of the contactor 68 may be controlled by a suitable normally-closed acceleration relay 70. Only the respective normally-closed contacts of the relays 69 and 70 have been shown in detail since such devices and their operating connections are well-known in the art.

The contactors 60, 62, 63, 64, 66, and 68 each has an operating winding referred to by the reference numeral of the respective contactor followed by the letter "w." The contactor 60 also has normally-open auxiliary contacts 60c, 60d, and 60e and normally-closed auxiliary contacts 60f, the contactor 62 also has normally-open auxiliary contacts 62c, 62d, and 62e and normally-closed auxiliary contacts 62f, the contactor 63 has normally-open auxiliary contacts 63b and normally-closed auxiliary contacts 63c, the contactor 64 also has normally-open auxiliary contacts 64b, and the contactor 66 also has normally-open auxiliary contacts 66b and normally-closed auxiliary contacts 66c.

35 A suitable master switch 71 having an off position intermediate of a reverse and a forward position is arranged to control the operation of the several contactors selectively and has a plurality of movable contact buttons 72 through 77 and a plurality of relatively stationary contact segments 78 through 83. The master switch 71 also controls the energization of an electromagnetic under-voltage relay 84 having an operating winding 84w and normally-open contacts 84a.

45 Further understanding of the control system of Fig. 5 and the cooperative functioning of the various limit control circuits will be obtained from the following description of its operation:

With the knife switch 48 closed and the master switch 71 in its "off" position, low frequency alternating current at relatively low voltage is available at the secondary of the transformer 46 but not circuit is completed. It is assumed that the carriage 40 is in its extreme right-hand position with the vane 44 covering the reactor 31 as indicated by dotted lines 88. When the master switch 71 is in its "off" position and power is available at the source conductors 61, an energizing circuit for the winding 84w of the under-voltage relay 84 is completed through the master contacts 72, 78, and 73 and through the normally-closed contacts 66a and 63c. Closure of the contacts 66a connects the master contacts 74 and 79 to the left-hand source conductor 61.

65 If the master switch 71 is moved into its reverse position at this time, an energizing circuit for the winding 62w of the reverse contactor 62 is completed through the master switch contacts 79, 81, and 77 and through the normally-closed contacts 69f. The reverse contactor 62 thereupon closes its contacts 62c and 62d to complete the reverse slowdown and final limit control circuits. The slow-down relay 58w responds to close its contacts 50a and 50b upon closure of the contacts 62c since the reverse slow-down limit cir-

cuit including the reactor 33, the capacitor 49, and the normally-closed contacts 62c is resonant. However, because the vane 44 is in the leakage field of the reactor 31 as indicated at 88, the reverse final limit control circuit through the contacts 62d, the reactor 31, the capacitor 51, and the winding 52w is not resonant and the relay 52 remains in its dropped-out position. Closure of the contacts 62e therefore does not at this time complete an operative circuit for the main line contactor 63 since the circuit to its winding 63w remains open at the contacts 52b. Consequently, although the contacts 62a and 62b are closed, the motor 34 does not operate because of the open circuit at the contacts 63a. Hence, with the carriage 40 at its right hand limit of movement, it is impossible to energize the motor 34 so as to move the carriage 40 further to the right.

If the master switch 71 is now moved into its forward position, an energizing circuit is completed for the winding 63w of the forward contactor 60 through the master switch contacts 79, 82, and 76 and the now reclosed contacts 62f. Resulting closure of the contacts 62c and 60d completes the forward slow down and final limit control circuits. The relay 52 again picks up due to completion of the forward slow-down limit circuit through the reactor 32, the capacitor 49 and the contacts 62c, and the relay 52 picks up due to completion of the forward final limit control circuit through the reactor 30 and the capacitor 51. Since the circuits just traced are both in resonance, the contacts 50a, 50b, 52a, and 52b close quickly. Closure of the contacts 50a completes a holding circuit for the relay 50 against subsequent opening of the contacts 66c. Closure of the contacts 52a and 52b completes a circuit for the winding 63w of the main line contactor 63 through the master contacts 79, 82, and 75 and the now closed contacts 60e. The resulting closure of the contacts 63a completes the circuit for the motor through the now-closed contacts 60a and 60b releasing the brake 54, and the motor 34 drives the carriage 40 to the left or in the forward direction. Closure of the contacts 63b completes an energizing circuit through the contacts 60e and the now-closed contacts of the plugging relay 69 for the winding 66w of the plugging contactor 66. Had the motor been plugged instead of having been started from rest as assumed, the contacts of the plugging relay 69 would have opened and would have remained open until the motor approached zero speed. The contactor 66 closes its contacts 66a upon energization of the winding 66w to short-circuit the resistor section 55p, and closes its contacts 66b to complete an energizing circuit for the winding 64w through the contacts 84a and 50b. The contactor 64 then responds to open at its contacts 64a, the armature shunt circuit through the resistor 65 and to close its contacts 64b. When power was first applied to the motor 34, the acceleration relay 70 opened its contacts, but after a time delay these contacts close and an energizing circuit for the winding 68w of the acceleration contactor 68 is then completed there-through and through the contacts 64b and 50b. The contactor 68 thereupon closes its contacts 68a to short circuit the remainder of the resistor 55, and the motor 34 accelerates to its maximum forward speed.

The carriage 40 now travels rapidly toward the left. When the vane 44 enters the field of the slow-down reactor 32, the resonance of the forward slow-down limit control circuit including

the reactor 32, the capacitor 49, and the winding 50w is suddenly impaired and the relay 50w drops out opening its contacts 50a and 50b. Opening of the contacts 50a interrupts the holding circuit for the relay 50 so that, when the vane 44 moves out of the field of the reactor 32, the relay 50 is not re-energized, the contacts 66c being open. Opening of the contacts 50b interrupts the circuits for the windings 64w and 63w. A portion of the resistor 55 is inserted in series with the motor 34 upon consequent opening of the contacts 68a and the resistor 65 is connected in parallel with the armature 34a upon consequent closure of the contacts 64a. The motor 34 is slowed down and continues to run at a slow speed as the carriage 40 approaches the locking head 45.

When the carriage 40 is substantially at its locking position within the locking head 45, the vane 44 enters the field of the reactor 30. This impairs the resonance of the forward final limit control circuit including the reactor 30, the capacitor 51, and the relay winding 52w, so that the relay 52 drops out opening its contacts 52a and 52b. Since the contacts 63c are open, opening of the contacts 52a opens the only remaining circuit for the under voltage relay 84 which thereupon opens its contacts 84a. Opening of the contacts 84a disconnects the master switch contact 74 from the source 61, and all energized contactors are immediately deenergized. The contacts 52b also interrupt the circuit for the winding 63w directly. The motor 34 is quickly deenergized and the brake 54 sets to stop the carriage 40 in locking position.

The master switch 71 must be returned to its off position in order to reclose the relay 84. Even after the relay 84 is reclosed, it is still impossible to reclose the main-line contactor 63 by moving the master switch 71 into its forward position since the impairment of resonance of the forward final limit control circuit due to the vane 44 being in the field of the reactor 30 prevents operation of the relay 52.

Operation of the motor 34 in the reverse direction for driving the carriage to the right from its locking position is not described in detail because it is apparent from the preceding description of forward operation. When the vane 44 enters the field of the reactor 33 with the reverse contactor 62 closed, impairment of resonance causes drop-out of the slow-down relay 50, and when the vane 44 enters the field of the reactor 31 with the reverse contactor 62 closed, impairment of resonance of its circuit causes drop-out of the relay 52 resulting in stopping of the carriage 40.

Thus having described my invention, I claim:

1. A limit control means comprising a moving machine element to be stopped at a limit of movement, an electric motor for moving said machine element toward said limit, a conducting vane carried by said machine element along a predetermined path as said machine element moves, a reactor having a leakage field which is in said path near said limit, an approximately tuned circuit including said reactor, a capacitor, and a winding of a relay, means responsive to operation of said relay for controlling said motor, and said relay being rendered operative upon impairment of approximate resonance of said tuned circuit resulting when said vane enters said leakage field.

2. A limit control means for an electric motor, forward switching means operable for connecting

the motor for forward operation, reverse switching means operable for connecting the motor for reverse operation, a forward approximately tuned circuit operative when approximately resonant to permit operation of said forward means and operative when its approximate resonance is impaired to prevent operation of said forward means, a reverse tuned circuit operative when approximately resonant to prevent operation of said reverse means and operative upon impairment of its approximate resonance to prevent operation of said reverse means, and means driven by said motor for impairing the approximate resonance of said circuits selectively depending upon the direction of rotation of said motor.

3. A limit control means comprising a pair of reactors mounted near opposite ends of travel of a machine element movable by an electric motor, forward and reverse electromagnetic switching means for said motor, a control circuit for said switching means, a series circuit including a capacitor and an operating winding of a relay having normally open contacts in said control circuit, and said switching means including means for connecting said series circuit to said reactors, selectively, depending upon the direction of rotation of said motor.

4. A limit control means comprising a reactor having an exposed external leakage field path, a conducting vane, a motive means for driving said vane and operative to move said vane into said leakage field path thereby to increase the reactance of said reactor, an electromagnetic device operative when energized to maintain said motive means operative at a relatively high speed, an energizing circuit for said electromagnetic device operative only when completed to maintain said device operative, an electromagnetic relay having an operating winding, a capacitor having a capacitive reactance at a predetermined frequency approximately algebraically equal to the sum of the reactance of said winding and said reactor at said frequency and when said vane is out of said leakage field path, means connecting said reactor, winding, and capacitor in series with each other in a circuit between a pair of terminals adapted to be connected to a source of power, the constants of said series circuit and relay being so related to each other and to a predetermined voltage of predetermined frequency that, when said terminals are connected to a source of said voltage and frequency, said relay is picked up when said vane is out of said leakage field path and said relay is dropped out when said vane is in said leakage field path, and said relay having contacts operative upon drop out of said relay for interrupting said energizing circuit.

5. A limit control means comprising a reactor having an exposed external leakage field, a conducting vane operatively connected to a movable machine element so as to be moved thereby in predetermined relation thereto in a path into and out of said leakage field thereby to change the reactance of said reactor, a motor for moving said element, an electromagnetic relay having an operating winding, a capacitor having a capacitive reactance at a predetermined frequency approximately algebraically equal to the sum of the reactance of said winding and said reactor at said frequency and with said vane out of said field, means connecting said reactor, winding, and capacitor in series with each other in a circuit and adapted to connect the circuit across a

source of substantially constant voltage of said frequency, means responsive to said relay for slowing down said motor, a second approximately tuned circuit including a second capacitor, a winding of a second relay, and a second reactor having a leakage field which is in said path spaced from said first field, means rendered operative upon operation of said second relay for stopping said motor, and said second relay being rendered operative upon impairment of approximate resonance of said second tuned circuit resulting when said vane enters the leakage field of said second reactor.

6. The limit control means of claim 1 characterized in that said means responsive to operation of said relay comprises an electromagnetic device operative when energized to permit said motor to operate at a high speed and operative when deenergized to cause said motor to slow down, and said relay has normally-open contacts in an energizing circuit for said device.

7. A limit control system comprising a conducting vane, a reactor having poles defining an exposed external field for leakage flux and which is adapted to receive said conducting vane, means operable to move said vane into said leakage field, an electromagnetic device operative when energized to render said means operative to move said vane into said leakage field and operative when deenergized to render said means operative to reduce the speed of said vane, an electromagnetic relay having an operating winding and operative when its winding is energized to cause energization of said device and operative when deenergized to cause deenergization of said device, a capacitor, means connecting said reactor, capacitor, and winding in a circuit across a source of alternating current of a given frequency, the constants of said circuit at said frequency and when said vane is out of said field being so related that said winding is energized, and said constants being so related that when said vane is in said field said winding is deenergized.

8. A limit control means comprising a reactor having an exposed external leakage field, a metallic vane operatively connected to a movable machine element so as to be moved thereby in predetermined relation thereto into and out of said leakage field, a motive means connected to said element and operative to move said element, an electromagnetic device operative when energized to maintain said motive means operative at a high speed, an electromagnetic relay having an operating winding, a capacitor having a capacitive reactance at a predetermined frequency approximately arithmetically equal to the sum of the reactance of said winding and said reactor at said frequency and when said vane is out of said leakage field, means connecting said reactor, winding, and capacitor in series with each other in a circuit and connecting the circuit across a source of alternating current of substantially constant voltage of said frequency, the electrical constants of said series circuit being so related to each other and to the voltage and frequency of said source that said relay is picked up when said vane is moved out of said leakage field and dropped out when said vane is in said leakage field, an energizing circuit for said electromagnetic device arranged to be controlled by said relay and completed by said relay to maintain said device energized while said relay is picked up and interrupted by said relay to deenergize said device while said relay is dropped out, where-

by the speed of said motive means decreases when said relay drops out.

9. A variable impedance limit control circuit comprising a reactor having poles defining an exposed external field for leakage flux and which field is adapted to receive a conducting vane, a conducting vane arranged to move in a path including said external field, a motive means connected to said vane for driving said vane in said path, a controller electrically connected to said motive means for controlling said motive means and including an electro-magnetic device having a control winding and operative when said control winding is energized to permit said motive means to move said vane into said external field and operative when said control winding is de-energized to reduce the speed of said vane, a capacitor, an electro-magnetic relay having an operating winding, a series circuit connecting said reactor, capacitor, and winding in series with each other and arranged for connection across a source of alternating current of constant frequency, the electrical constants of said circuit being so related to each other that, if connected to a source of predetermined voltage and low and constant frequency with said leakage field substantially free of conductive material, said relay will pick up, the electrical constants of said circuit being further so related to each other that, if connected to said source, said circuit will become approximately resonant with said relay picked up, said relay being capable of being held in its picked up position by the current that flows in said circuit at approximate resonance, and the electrical constants of said circuit being further

so related to each other that, if connected to said source, said approximate resonance can be impaired to reduce the circuit current to below the drop-out current of said relay by insertion of the vane in the leakage field, contacts on said relay which open upon drop out of said relay, and an energizing circuit for said control winding having said contacts in series with said control winding.
